US0D1048600S

(12) **United States Design Patent** (10) **Patent No.:** **US D1,048,600 S**
(45) **Date of Patent:** **** Oct. 22, 2024**

(54) **DEVICE FOR REMOVING ANIMAL EXCREMENT**

(71) Applicant: **PLANDDO CO., LTD.**, Taipei (TW)

(72) Inventors: **Tsung-Te Sun**, Taichung (TW);
Chao-Shun Liang, Tainan (TW);
Chia-Hsin Wu, Taichung (TW);
Ping-Yun Su, Hsinchu (TW); **Yu-Huai Yang**, Kaohsiung (TW)

(73) Assignee: **PLANDDO CO., LTD.**, Taipei (TW)

(**) Term: **15 Years**

(21) Appl. No.: **29/824,753**

(22) Filed: **Jan. 27, 2022**

(30) **Foreign Application Priority Data**

Jul. 28, 2021 (TW) 110303930
